UNITED STATES PATENT OFFICE

MOSES W. H. WILSON, OF EAST LANSING, MICHIGAN, ASSIGNOR TO MOTOR WHEEL CORPORATION, OF LANSING, MICHIGAN, A CORPORATION OF MICHIGAN

VARIABLE SPEED SURFACING MACHINE

Application filed April 8, 1929. Serial No. 353,295.

My invention has to do particularly with an improvement in machines for surface-treating, as by sanding or filling, objects having other than a cylindrical contour. It is old to surface treat wood wheel spokes or similar objects by rotating the spoke with its barrel portion in contact with an abrading or cutting surface.

A traveling belt having an abrasive face has been employed in connection with means not only for rotating but advancing the spoke bodily through a cycle from the point of entry to the point of discharge from the machine.

Similarly, traveling belts have been coated with filler paste and applied to the contacting face of rotating objects such as spokes, one belt being employed for applying the filler and a second belt for rubbing it into the pores and wiping off the surplus, the spoke being in the meantime progressively advanced and rotated.

Such machines and practices have been predicated upon the assumption that the work pieces are truly cylindrical, the progressive movement of the belts and work as also the rotation of the latter being constant, under which conditions uniformity of result would follow.

However, non-uniform results follow where, as in the case of many spoke designs, the body treated is of non-cylindrical shape, elliptical, oval, squared, or otherwise. In such circumstances, a constant speed of rotation will result in those portions having a larger radius being acted upon to a greater degree than the smaller radius,—the surface area corresponding to the major axis as compared with the surface area corresponding to the minor axis. For instance, the abrasive effect will be greater on the corners than on the flat face of a squared spoke, and on the sharper curvature than that of flatter area in the case of an elliptical spoke.

To compensate for such conditions, it is

proposed, according to my invention, to vary the speed of rotation of the spoke through recurring cycles of acceleration and deceleration corresponding to the periods when the portions of different contour are in contact with the surfacing belt or other medium,—accelerated when the more sharply curved area is in contact and decelerated when the flatter area is being acted upon.

To this end I preferably, though not necessarily, maintain a constant forward travel of the surfacing medium, but provide by means of irregular gearing, eccentric or elliptical, for advancing and rotating the spokes at varying speeds at predetermined positions.

In order that the invention may be readily understood and readily practiced, a preferred embodiment of the same is set forth, for illustrative and not restrictive purposes, in the accompanying drawings, wherein

Fig. 1 is a side elevation of those portions of a machine necessary to an understanding of the invention;

Fig. 2 is an end elevation;

Fig. 3 is a diagrammatic view illustrating

an elliptical spoke in section with recurring

positions of the same in dotted lines; and

Fig. 4 is a spoke section illustrating the

contour of the squared spoke.

For ease of understanding the type of machine upon which the present invention is an improvement, reference is had to Patent No. 1,660,535 issued February 28, 1928 upon the application of A. S. Van Halteren, a machine there set forth as applied to the filling of spokes preliminary to painting and a machine equally well adapted to surfacing by sanding. Various details of assembly incident to machines of that type are not deemed necessary to be completely illustrated herein, being well understood in the art.

Having reference to the drawings, a belt 11, suitably driven, passes over pulleys 12 and 13, while a second belt 14, suitably driven, traverses pulleys 15 and 16. Belt 11 may

advantageously be faced with an abrading material such as sand of coarse texture, while belt 14 may be faced with a finishing abrasive material of finer texture; or belt 11 may be coated with a filler paste for application to the objects being treated, while the belt 14 may serve as a wiping belt for rubbing the material into the pores of the wood and wiping off the surplus. The belts will be hereinafter referred to, without restrictive intent, as abrading belts and the machine as a sanding machine, it being understood that without substantial modification the machine may be employed for variously surfacing objects.

Upon the shaft 17, driven by suitable means, is mounted a cage-like frame or reel comprising spaced frame members 18, 19, 20 and 21, the member 19 provided with centering head chucks 22 and the member 20 with centering tail spindles 23 spring-pressed at 24 for ease of inserting and removing from the machine the spokes or other work pieces illustrated as having their head portions 25 seated in the head chucks 22 and their barrel portions 26 centered by the spindles 23. In Fig. 2, a spoke is shown as missing, this for the purpose of illustrating the retraction of the spindle against its spring 24 prior to inserting a spoke.

Upon the axle 27 of each of the head chucks is mounted a pinion 28. The head chucks and tail spindles are mounted in opposed coaxial relation to each other and in an annular series about the shaft 17. A stationary rear gear 29 is fixed upon the machine frame and serves as a toothed rack with which each of the pinions 28 mesh and by which they are rotated upon their respective axes as they revolve in an orbit about the shaft 17.

The objects to be treated, spokes for example, having one end seated in the head chucks 22 and the other end releasably held by the spring-pressed tail spindles 23, occupy a position transverse to their path of revolution about the reel axis and also transverse to the path of the abrading belts 11 and 14, the planes of revolution including barrels of the spokes being parallel to and included within planes of travel of the belts.

The barrels 26 of the spokes are successively brought into and maintained in continuous substantially constant pressure contact with the belt 11 by the rotation of the reel and the belt tension and, as they are at the same time being rotated by the pinions 28, the barrel surface is subjected to an abrasive action by the belt. As the spokes progress, after leaving contact with the abrading belt 11, they come into contact with the second belt 14, whereby the surface is further treated. The spokes are then released from the chucks and replaced by others before the chucks next reach the abrading belts.

The mechanism thus far described and operating in the manner set forth would serve to surface the spoke barrels uniformly, provided the barrels were of cylindrical contour or circular cross section. The modern wheel spoke is, however, not usually circular in cross section or of cylindrical surface contour but departs from regularity of curvature, tending towards an elliptical section, as shown in Fig. 3, or a squared section, as shown in Fig. 4. With the machine as thus far described, employed for sanding, the area corresponding to the major axis of the elliptical spoke and corresponding to the corners of the squared spoke would be subjected to a greater abrading action than the area corresponding to the minor axis, the result being a tendency towards cutting the spoke down to a circular section.

In order to compensate for this difference in contour, the train of gearing connecting the drive pulley with the axle 17 of the reel comprises gear members of non-circular, eccentric or elliptical shape instead of circular gears. Eccentric gear elements are illustrated, although it is to be understood that elliptical gears or other equivalent elements may be substituted without departure from the invention.

To illustrate, the drive pulley 30 transmits power to the drive shaft 31 journaled in the yoke 31^a and carrying a pinion 32 in mesh with a pinion 33. Upon the shaft 33^a of pinion 33 is secured an eccentric gear 34 which is in mesh with another eccentric gear 35 mounted on another shaft 35^a carrying a pinion 36, which latter pinion is in mesh with a large pinion 37 having fixed upon its shaft a smaller pinion 38 which in turn meshes with and serves to drive the large gear 39 fixed upon the shaft 17 of the reel.

Obviously other combinations of gears in train may be employed, whereby the constant speed of the power shaft 31 is transmitted to the ring gear 29 as a varying speed due to the incorporation in the train of one or more eccentric or elliptical gears.

The gear ratio is such that there are two accelerations and alternate retardations of the head chucks during each rotation of the chuck and spoke held thereby.

The two cycles of acceleration and retardation during one revolution of the spoke would apply where an elliptical spoke is being surfaced, such as that illustrated in Fig. 3 of the drawing. If, however, a spoke of the cross section as shown in Fig. 4 were being surfaced, there would be, during each rotation of the spoke, a cycle comprising four accelerations and four decelerations or retardations, the accelerations corresponding to the time when the corners were in contact with the sanding belt and the four retardations corresponding to the time when the flat surfaces of the spoke were being sanded.

In many cases but one surfacing belt would be employed and the spoke could be given either one or more complete rotations while in contact with the belt. In other cases a second belt would advantageously be employed to give a finer finish to the article; all to accord with the particular kind of work being done and the nature of the surface treatment.

It will thus be observed that according to my invention a surfacing machine is provided which by a suitable change of gearing, within the skill of any mechanic, will uniformly operate upon the surface of work pieces having other than a cylindrical contour as distinguished from prior machines of this general type wherein non-uniform results follow a uniform rotation of the work while being treated; that the invention as set out is adapted for embodiment in machines of this type when employed for surfacing in many ways other than that of sanding.

I claim:

1. In a machine for surface treating articles of non-cylindrical contour, the combination with a uniformly traveling treating surface, means for moving the article bodily and means for rotating the article in rubbing contact with said surface, of means for varying the axial speed of rotation through a cycle during the period of such contact.

2. In a machine for surface treating articles of non-cylindrical contour, the combination with a treating surface, and means for bodily moving and rotating the article in rubbing contact with said surface, of means for increasing the speed of bodily movement and speed of rotation of the article when the area in contact corresponds to a greater radius and decreasing the speed when the contact area corresponds to a smaller radius.

3. In a machine for surface treating articles of a non-cylindrical contour, the combination with a treating surface, a reel revolving peripherally adjacent said surface, an annular toothed rack disposed adjacent the reel periphery, a plurality of article-holding chucks rotatably mounted on the reel periphery in geared relation to the annular rack, and means for revolving the reel at variable speeds with the surfaces of the articles carried in the chucks in rubbing contact with the treating surface.

4. In a machine for surface treating articles of a non-cylindrical contour, the combination with a treating surface, a reel revolving peripherally adjacent said surface, an annular toothed rack disposed adjacent the reel periphery, a plurality of article-holding chucks rotatably mounted on the reel periphery in geared relation to the annular rack, and means for revolving the reel at variable speeds with the surfaces of the articles carried in the chucks in rubbing contact with the treating surface, the speed of revolution of the reel and consequent forward travel and

rotation of the chucks being increased when areas of the articles corresponding to a greater radius are in contact with the treating surface and decreased when areas are in contact corresponding to a smaller radius.

5. In a machine for surface treating articles of a non-cylindrical contour, the combination of a moving surfacing belt, a reel revolving peripherally adjacent the belt, an annular toothed rack disposed adjacent the reel periphery, a plurality of article-holding chucks rotatably mounted on the reel periphery in geared relation to the annular rack, and means for revolving the reel at variable speeds with the surfaces of the articles carried in the chucks in rubbing contact with the belt.

6. In a machine for surface treating articles of a non-cylindrical contour, the combination of a moving surfacing belt, a reel revolving peripherally adjacent the belt, an annular toothed rack disposed adjacent the reel periphery, a plurality of article-holding chucks rotatably mounted on the reel periphery in geared relation to the annular rack, and means for revolving the reel at variable speeds with the surfaces of the articles carried in the chucks in rubbing contact with the belt, the speed of revolution of the reel and consequent forward movement and rotation of the chucks being increased when areas of the articles corresponding to a greater radius are in contact with the belt and decreased when areas are in contact corresponding to a smaller radius.

7. In a machine for surface treating articles of a non-cylindrical contour, the combination of a moving surfacing belt, a reel revolving peripherally adjacent the belt, an annular toothed rack disposed adjacent the reel periphery, a plurality of article-holding chucks rotatably mounted on the reel periphery in geared relation to the annular rack, and means comprising a gear train including eccentric gears for revolving the reel at variable speeds with the surfaces of the articles carried in the chucks in rubbing contact with the belt, the speed of revolution of the reel and consequent forward movement and rotation of the chucks being increased when areas of the articles corresponding to a greater radius are in contact with the belt and decreased when areas are in contact corresponding to a smaller radius.

8. In a machine for surface treating articles, a treating belt, means for imparting to the belt a progressive traveling movement in an arcuate path, holders for the articles to be treated, means for moving said holders in an orbit tangential to the arc of the belt travel and in rubbing contact therewith, means for axially rotating said holders and articles, and means for varying the axial speed of rotation and the surface speed of rubbing contact periodically.
